C. H. WILDER AND J. M. WILDER, OF NEW YORK, N. Y.

Letters Patent No. 65,978, dated June 18, 1867.

IMPROVEMENT IN NIPPLE-SHIELD.

The Schedule referred to in these Letters Patent and making part of the same.

TO ALL WHOM IT MAY CONCERN:

Be it known that we, C. H. WILDER and J. M. WILDER, of the city, county, and State of New York, have invented a new and improved Nipple-Shield; and we do hereby declare that the following is a full, clear, and exact description thereof, which will enable others skilled in the art to make and use the same, reference being had to the accompanying drawings, forming part of this specification, in which—

Figure 1 represents a longitudinal central section of this invention taken in the plane indicated by the line $z z$, fig. 2.

Figure 2 is a transverse section of the same, the lines $y y$, fig. 1, indicating the plane of section.

Similar letters of reference indicate like parts.

This invention consists in the arrangement of a screen in combination with a nipple shield in such a manner that by said screen the nipple is prevented from being drawn out any further than desirable, and the usefulness of the nipple-shield is materially improved. The screen is made adjustable, so that its position can be regulated to correspond to nipples of different sizes.

A represents a nipple-shield made of India rubber, or other suitable material, and attached to the end of a tube, B, of glass, or other similar material, in the ordinary manner. With this nipple-shield we have combined a screen, α ; made of glass, or any other suitable material, and perforated with a number of small holes, through which the milk passes to the spout. This screen serves to support the nipple, and it prevents said nipple being drawn in any further than desirable. Instead of fastening the screen firmly in the tube B, however, we have attached the same to a slide, C, which is also made of glass, or other suitable material, and provided with a packing-ring, b , so that it moves air-tight in the tube B. By these means the screen is rendered adjustable, so that its position can be regulated to correspond to the size of different nipples. By the attachment of our screen the value of the nipple-shield is considerably increased, and said shield is rendered much more convenient in its application than a nipple-shield of the ordinary construction.

Having thus described our invention, we claim as new, and desire to secure by Letters Patent—

1. The arrangement of a screen, α , in combination with the nipple-shield A, substantially as and for the purpose described.
2. The adjustable slide C, in combination with the screen α and nipple-shield A, substantially as and for the purpose described.

C. H. WILDER,
J. M. WILDER.
